S. WILEY

FUSE

Filed Nov. 8, 1923

INVENTOR
Samuel Wiley
BY *W. H. Roach* ATTORNEY

UNITED STATES PATENT OFFICE.

SAMUEL WILEY, OF METUCHEN, NEW JERSEY.

FUSE.

Application filed November 8, 1923. Serial No. 673,445.

(GRANTED UNDER THE ACT OF MARCH 3, 1883; 22 STAT. L. 625.)

To all whom it may concern:

Be it known that I, SAMUEL WILEY, a citizen of the United States, and a resident of Metuchen, county of Middlesex, and State 5 of New Jersey, have invented an Improvement in Fuses, of which the following is a specification.

The invention described herein may be used by the Government, or any of its officers or employees in prosecution of work for the Government, or by any other person in the United States, without payment to me of any royalty thereon, in accordance with the act of March 3, 1883.

15 The present invention relates to fuses and more specifically to fuses of the powder delay type.

The primary object of my invention is the provision of a fuse which will positively prevent explosion of the projectile with which the fuse is to be used until the projectile has moved a safe distance on its trajectory away from the thrower or user.

20 A further object is the provision of a fuse which will not only prevent premature explosion, but which will prevent explosion after a predetermined time in flight has elapsed.

With the foregoing and other objects in view, my invention resides in the novel arrangement and combination of parts and in the details of construction hereinafter described and claimed, it being understood that changes in the precise embodiment of 35 the invention herein disclosed may be made within the scope of what is claimed without departing from the spirit of the invention.

A preferred embodiment of my invention is illustrated in the accompanying drawing, 40 in which:

Fig. 1 is a view in side elevation of a hand grenade with my fuse attached thereto;

Fig. 2 is a vertical section through the grenade and fuse; and

45 Fig. 3 is a view in rear elevation of Fig. 1.

Referring to the drawings by numerals of reference:

I have shown at 5 a suitable projectile in this instance, a hand grenade provided with 50 two chambers 6 and 7 separated by a partition 8. The chamber 6 is adapted to receive a suitable explosive 9 while the chamber 7, in the preferred embodiment of my invention, is open at its outer end to receive

a fuse casing 10. This fuse casing consists, 55 preferably, of a closure member 11 threaded or otherwise secured in the opening formed in the chamber 7 and formed on its inner side with a dished surface 12. The fuse casing is provided on its outer surface with an 60 externally screw threaded projection 13 hollowed to receive a primer 14.

The projection 13 is adapted to be threaded into the usual nipple 15 which serves to carry the customary hand grenade lever. 65 As shown, this member 15 is formed with a lug 16 for a purpose which will hereinafter appear. For exploding the primer 14 I employ a hammer 17 of any suitable type, preferably, as shown, actuated by a spring 18 70 which is wound on the pin 19 secured in the nipple and which has one end contacting with the hammer. The hammer is normally held in inoperative position by the customary lever or handle 20, which is approximately L shaped and which has a projection 21 engaging the lug 16 and which is removably secured to the nipple against the action of the spring 18 and hammer by means of a cotter pin 22 which passes 80 through the nipple and a pair of ears formed on the handle or lever.

The structure of the hand lever and firing mechanism is that customarily employed with the type of grenade shown and forms 85 no part of my invention. The hammer is actuated by the spring 18, in the usual manner, upon withdrawal of the cotter pin 22 which is equipped with a ring 23 to permit its ready removal from engagement with 90 the nipple and the lever.

The inner wall of the chamber 7 which is formed by the partition 8 is dished as at 24 in a manner similar to the dishing of the surface 12 of the fuse casing. Mounted between the two surfaces 12 and 24 and with their outer faces normally seated against these surfaces are a pair of normally separated blocks 25 and 26.

The outer face of one of these blocks, as 100 for instance, the block 25, is formed with an annular groove adapted to receive a powder train 27 acting as a delay charge which as will be explained hereinafter serves as a means for actuating the explosive with 105 which the grenade is charged. The other of the blocks as for instance the block 26, is formed with a projection 28 adapted to

reciprocate in a recess 29 provided in the other block which recess is filled for a portion of its length with a powder pellet 30 for a purpose which will hereinafter be explained. The projection 28 and the block 26, are hollowed to receive a delay charge 31. The powder pellet 30 and the delay charge 31 are so arranged as to prevent movement of the projection 28 in the block 25 until the powder pellet and the delay have been consumed.

In the preferred embodiment of my invention, the block 25 is provided with an aperture 32 by means of which the flash from the powder pellet may travel to the delay charge or powder train 27.

Any suitable means may be provided for maintaining the blocks 25 and 26 apart in flight. As shown, the inner surfaces of the blocks are formed with annular grooves 34 and seated in these grooves and interposed between the two blocks is a coil spring 35.

The face 24 of the partition 8 is formed with a series of grooves 36 adapted to receive a felt washer 37 and with a central recess 38 in which is seated a powder pellet 39.

Any suitable means may be provided for actuating the explosive charge of the grenade. As shown, the partition 8 is recessed as at 40 to receive a detonator casing 41 secured by a screw head 42 in the recess formed in the partition. An aperture 43 is formed in the partition in line with the pellet 39 and the screw head is provided with side recesses 44 and a central aperture 45 by means of which the flash from the pellet 39 may be communicated to the detonator in the detonator casing so that the detonator will break the casing 41 and the wall intervening between it and the explosive charge to actuate the explosive and fragmentate the grenade.

The operation of my fuse is as follows: The soldier using the grenade first withdraws the cotter pin 22. As the grenade is projected the lever 20 is thrown off by the force of the spring 18 which moves the hammer to strike the primer 14. The flash from the primer passing through an opening 46 in the fuse casing ignites the delay 31. This delay may be of any predetermined duration, its function is to cooperate with the powder pellet 30 to prevent relative movement of the blocks 25 and 26 until the grenade has moved a safe distance away on its trajectory. When the delay and the powder pellet are consumed the fuse is armed, the spring 35 serving to maintain the blocks 25 apart in flight. If the projectile strikes before the fuse is armed the grenade is a dud. When the powder pellet 30 is ignited the flash from the same passes through the aperture 32 to ignite the delay charge 27. This delay charge may be of any predetermined

length. The spring 35 in flight holds the block 25 and the delay charge 27 contained therein flush against the felt washer 37 and hence the delay charge cannot ignite the powder pellet 38 until the block 25 is moved away from the surface 24 of the partition 8 as on impact when the felt washer 37 is thrown out of the recess 36. As stated the delay 27 is of a fixed duration; if the grenade strikes after it is armed and while the delay 27 is still burning the felt washer will be thrown out of the recesses 36 and the delay will be able to ignite the powder pellet 39 which in turn, will actuate the detonator to explode the grenade. If the projectile strikes after the delay 27 has burnt out the grenade is a dud.

The fuse then which forms the subject of this invention prevents explosion of the grenade until a predetermined time measured by the length of the delay charge 31 and the size of the powder pellet 30 has elapsed and further prevents explosion of the grenade after a predetermined time measured by the length of the powder train 27 has expired.

To prevent movement of the blocks 25 and 26 relative away from each other after impact under force of the spring 25, I preferably provide one of the blocks, as shown the block 26, with a spring dog 47 which is attached at one end to the block 26 and which is adapted to engage selectively in grooves 48 formed in the other block.

The inclined surfaces formed by the dished faces 24 and 12 permit my fuse to function no matter how it strikes, the fuse blocks riding upon these faces whatever the position of impact and being forced by these faces together against the action of the spring 35.

While I have described my fuse as applied to a hand grenade, it is clear that the same may be used with a rifle grenade by unthreading the nipple 15 from the projection 13. The fuse, moreover, is not limited to use as a base fuse but may be positioned any convenient location on the grenade. The fuse, moreover, is by no means limited to use with grenades being applicable to any suitable projectile.

As shown, the grenade may be filled with an explosive material through an opening 49 formed in the head of the grenade and normally closed by a nut 50 screw threaded or otherwise secured therein.

I claim:

1. A fuse for projectiles embodying a casing formed with oppositely directed dished seats, two normally separated blocks maintained in said casing and adapted to rest at their outer faces in said seats, said blocks being adapted to move toward one another on impact, one of said blocks provided with a powder train of predetermined length adapted to explode said projectile when said

blocks are moved toward one another, means interposed between said blocks and maintaining said blocks apart in flight, a projection on one of said blocks, said projection being hollowed out to receive a delay charge, the other block provided with a recess adapted to receive said projection and with an opening communicating with said powder train, a powder pellet in the recess 10 adapted to prevent movement of the blocks toward one another until the delay charge and pellet have been consumed and a primer adapted to ignite the delay charge.

2. A fuse for projectiles embodying two normally separated blocks adapted to move toward one another on impact, one of the blocks provided with a powder train of predetermined length adapted to explode the projectile when the blocks are moved toward 20 one another, means for maintaining the blocks apart in flight and a powder train interposed between the blocks adapted to prevent movement of the blocks toward one another until after a predetermined time in flight has elapsed.

3. A fuse for projectiles embodying two normally separated blocks adapted to move toward one another on impact, one of the blocks provided with a powder train of predetermined length adapted to explode the projectile when the blocks are moved toward one another, means maintaining the blocks apart in flight and means preventing movement of the blocks until after a predetermined time in flight has elapsed.

4. A fuse for projectiles embodying two normally separated blocks capable of relative axial movement on impact, one of the blocks provided with a powder train of predetermined length adapted to explode the projectile, said powder train being op-

erable only when the blocks are moved together, means for maintaining the blocks apart in flight and means preventing movement of the blocks until after a predetermined time in flight has elapsed. 45

5. A fuse for projectiles embodying a delay charge of predetermined length adapted to be moved to operative position by the force of impact to actuate the explosive with 50 which the projectile is charged, means preventing movement of the delay charge until a predetermined time has elapsed after the discharge of the projectile, and means for maintaining the delay charge in inoperative 55 position during flight.

6. A fuse for projectiles embodying two normally separated blocks adapted to move toward one another on impact, one of the blocks provided with a powder train of predetermined length adapted to explode the projectile when the blocks are moved toward one another, means for maintaining the blocks apart in flight, and a powder train interposed between the blocks adapted 60 to prevent movement of the blocks toward one another until after a predetermined time in flight has elapsed and adapted to initiate combustion of the first mentioned powder train. 65

7. A fuse for projectiles embodying two normally separated blocks adapted to move toward each other on impact, one of the blocks provided with means for exploding the projectile when the blocks are moved toward each other and means preventing the movement of the blocks until after a predetermined time in flight has elapsed and initiating action of the projectile exploding 70 means. 75

SAMUEL WILEY.
